UNITED STATES PATENT OFFICE.

JOSEPH GWIZDOWSKI, OF DETROIT, MICHIGAN.

TUFTING-MACHINE.

1,360,522.

Specification of Letters Patent. Patented Nov. 30, 1920.

Application filed December 28, 1918. Serial No. 268,763.

To all whom it may concern:

Be it known that I, JOSEPH Gwizdowski, a citizen of the United States, and a resident of Detroit, in the county of Wayne and State of Michigan, have invented certain new and useful Improvements in Tufting-Machines, of which the following is a specification.

These improvements are especially applicable to the machine shown by the patent to Mathewson, No. 1,193,708, dated August 8, 1916, and have the same object as that set forth in the patent to Dillon, No. 1,211,924, dated January 9, 1917, and consist in means for forming a knot in a loop in the tufting twine at one side of a mattress and for causing the needle to draw the knot through to the opposite side of the mattress.

As the mechanism of the complete machine is fully described in the Mathewson patent, the drawings of the present device show the various parts merely conventionally, and Figure 1 is a side elevation of the tufting machine and Fig. 2 a section of the twine gripping mechanism on the line 2—2 of Fig. 1.

Similar reference characters refer to like parts throughout the several views.

The frame of the machine comprises an upright 1 and an arm 2 which has a head 3 at its outer end. The base 4 carries a knotter 5, and in practice a suitable table or platform will be employed to support the mattress 6 which is to be tufted, above the knotter. The head 3 carries the usual compressor which may be moved by a lever 7 which is pivoted on the frame and operated in any suitable manner. The head 3 also carries a needle 8 and a lever 9 for operating the needle to cause it to penetrate the mattress and be withdrawn therefrom, the usual guides being provided.

In the mechanism described in the Mathewson patent, the untufted mattress is compressed upon the stationary head associated with the knotter, a tuft is fed into place on each side of the mattress. The needle 8 is then forced downwardly through the mattress, carrying with it the tufting twine and in its descent the needle pierces the mattress and enters the knotting mechanism where the loose end of the twine is gripped. The needle then rises, leaving the strand of twine in its path. The mattress and needle then move laterally relative to each other sufficiently to carry the twine

across the upper tuft and the needle then descends, carrying the second strand of twine through the mattress parallel to the first strand. The knotter then knots the first 60 and second strands together across the lower tuft. In the Mathewson machine the twine is cut between the needle and the mattress after the needle has moved up to its original position ready for its next operation. 65 The loose ends of the first strands of twine depended from the knot at the bottom of the mattress and had to be cut off by hand after the tufting of the mattress had been completed. A second waste end of twine is the 70 third strand which extends up from the knot to the twine cutter at the top of the mattress. This waste is described in the aforesaid patent to Dillon.

The twine 10 passes to the upper end of 75 the needle bar 12 from a cop or ball 13 and its movements must be free under normal conditions so that it will not pull out of the eye of the needle. In order to pull the knot from the bottom to the top of the mattress means must be provided to force the 80 twine to move up with the needle after the knot has been tied as the mere releasing of the end of the first strand before the needle reaches the upper end of its stroke is not 85 sufficient to prevent the twine slipping through the eye of the needle. I have found that simply gripping the twine between the cop and the needle bar just before the final 90 upward movement of the needle is sufficient to force the twine to move upward with the needle.

In the drawings, the cop 13 is below the opening at the upper end of the needle bar into which the twine passes. I have mounted 95 a pin 16 in the arm 2 and on its end is a head or abutment 17 having an inclined surface adjacent the wedge 18 which is slidable on this pin. A disk 19 is rotatable on the axis 20 and a rod 22 connects the pin 23 on this disk to the wedge 18. A link 24 carries a roller 25 at the lower end which is engaged by the cam ring 26 on the disk 27 secured to the main shaft of the machine. The upper end of the link 24 connects to the pin 28 100 on the disk 19. A spring 29 connects to the wedge to withdraw it.

At each cycle of the machine as the needle is rising after the knot has been tied, the cam 26 pulls down the link 24 and turns 110 the disk 19 to pull over the wedge 18 to cause it to grip the twine. As the needle

rises the twine being held back, the knot necessarily is pulled up from the bottom to the top of the mattress. The twine is then immediately released. The twine is cut 5 above the mattress when the knot has come to the top.

It will be understood that many other devices may be substituted for that shown and described for preventing the twine from 10 slipping down through the eye of the needle as the needle rises after the knot has been tied, but I have found that means to grip the twine between the cop and the needle is very effective:

15 I claim:—

1. In a tufting machine, in combination with a reciprocating needle for carrying twine several times through a mattress where it may be knotted below the mattress, and intermittently acting means for preventing the twine from slipping through the needle as the needle rises after the knot has been tied to cause the needle to pull the knot up 20 to the top of the mattress.

25 2. In a tufting machine, in combination with a reciprocating needle for carrying twine several times through a mattress where

it may be knotted below the mattress, and intermittently acting means for preventing the twine from slipping through the needle 30 as the needle rises after the knot has been tied to cause the needle to pull the knot up to the top of the mattress, said means consisting of a device for gripping the twine at a point between the cop and needle bar. 35

3. In a tufting machine, in combination with a reciprocating needle for carrying twine several times through a mattress where it may be knotted below the mattress, and intermittently acting means for preventing 40 the twine from slipping through the needle as the needle rises after the knot has been tied to cause the needle to pull the knot up to the top of the mattress, said means comprising a wedge and an abutment between 45 which the twine normally passes freely, and a cam for moving the wedge to cause the twine to be gripped between it and the abutment.
